UNITED STATES PATENT OFFICE.

CHARLES HERMAN VIOL, OF PITTSBURGH, PENNSYLVANIA, ASSIGNOR TO STANDARD CHEMICAL COMPANY, OF PITTSBURGH, PENNSYLVANIA.

TOOL.

Application filed January 21, 1922. Serial No. 530,921.

To all whom it may concern:

Be it known that I, CHARLES H. VIOL, a citizen of the United States, and a resident of Pittsburgh, in the county of Allegheny and State of Pennsylvania, have invented 5 certain new and useful Improvements in Tools; and I do hereby declare the following to be a full, clear, and exact description of the invention, such as will enable others 10 skilled in the art to which it appertains to make and use the same.

This invention relates to improvements in tools and more particularly to such as are especially adaptable for use in manipulating 15 two-part metal screens in which tubes containing radium salts or compounds are contained.

It is important in the handling of radium tubes that the operator shall not be compelled to apply his fingers directly to the tubes. The tube containing the radium salt or compound is placed in a metal screen made in two parts screwed together, said parts comprising a tubular body portion and 20 a cap having threaded connection therewith. The cap portion of the screen is made with an eye at one end, and it is an object of my invention to provide a tool which can be manipulated with one hand and caused to 25 have locked connection with the eye of the screen cap and turned bodily to rotate the screen cap to screw it to or unscrew it from the body portion of the screen while said body portion is being held by a suitable 30 tool of the forceps type.

With this and other objects in view, the invention consists in certain novel features of construction and combinations of parts as hereinafter set forth and pointed out in 40 the claim.

In the accompanying drawings, Figure 1 is a perspective view of my improved tool with the arms in their open or separated positions. Figure 2 is a view showing the 45 tool in closed position as when in use, and Figures 3 and 4 are sectional views showing details of construction.

My improved tool comprises two spring arms 1 and 2 having their rear end portions 50 united, as at 3, and formed to provide a handle 4. The spring arms 1 and 2 taper from their intermediate portions toward their free ends and the arm 2 may be roughened or serrated as at 5 to prevent slipping of the user's fingers. The free end 55

of the arm 1 is provided with a pointed pin 6 projecting toward the arm 2 and the latter is made with a hole 7 to receive said pin. The perforated free end portion of the arm 2 is recessed as at 8 for the accommodation 60 of the eye on the cap member of a radium tube screen.

A slide 9 is mounted on the arm 1 and is guided by a pin 10 and a screw 11 projecting from said arm and entering an elongated 65 slot 12 in said slide. At its forward end, the slide 9 is provided with curved jaws 13 adapted, when the slide is moved rearwardly to engage the tapering portion of the arm 2 and serve to lock the arms 1 and 2 together 70 as indicated in Figs. 2 and 3 and thus prevent possibility of accidental disengagement of the tool from the eye of the screen cap. To facilitate manipulation of the locking 75 slide, the latter is provided near its rear end with a serrated button or enlargement 14.

In using the device, the operator will cause the arms 1 and 2 to approach each other so that the pin 6 will pass through the eye of a screen cap and through the hole 7 near the free end of the arm 2,—the body portion of the screen being held by the operator with a suitable tool of the forceps type. After the tool shall have been 80 connected with the screen cap as above explained, the operator will move the locking slide rearwardly so that its jaws will grasp the side portions of the arm 2 where the taper of said arm is such as to cause the 85 curved jaws to partially embrace the same.

The operator will now turn or rotate the tool on its own axis and thus cause the screen cap to rotate and to be screwed onto or from the body portion of the screen. By moving the locking bar forwardly so that the jaws 90 thereof will become disposed at a part of the tapering arm 2 which has less diameter than the space between said jaws, the arms will be released, one from the other, and their 95 resilience will cause them to spring apart and become released from the eye of the screen cap.

Having fully described my invention what I claim as new and desire to secure by Letters-Patent, is:

A tool for manipulating the cap of a radium screen, comprising two resilient arms united at one end and each tapering toward its free end, one of the arms having a hole near its free end and a recess in its 100 110

inner side immediately adjacent said hole forming a seat for the eye of a screen cap, and the other arm terminating in a lateral pin adapted to pass through the eye of a screen cap and enter the hole in the first-mentioned arm, a slide mounted on one arm and having a longitudinal slot between its ends, members passing through said slot and carried by the arm to guide the slide and hold it to the arm, and jaws carried by the slide and adapted to embrace both arms

to lock them together, the ends of the jaws being free whereby to release the arms when moved toward the free ends of the arms.

In testimony whereof I have signed this 15 specification in the presence of two subscribing witnesses.

CHARLES HERMAN VIOL.
